UNITED STATES PATENT OFFICE.

GEORGE H. MAURER, OF WASHINGTON, DISTRICT OF COLUMBIA.

BILL-FILE.

SPECIFICATION forming part of Letters Patent No. 794,994, dated July 18, 1905.

Application filed September 6, 1904. Serial No. 223,491.

To all whom it may concern:

Be it known that I, GEORGE H. MAURER, a citizen of the United States, residing at No. 611 Seventh street northwest, Washington, 5 District of Columbia, have invented new and useful Improvements in Bill-Files, of which the following is a specification.

My invention relates to bill-files which cut out the openings in bills, letters, or the like 10 when they are placed upon the serrated upper ends of vertical tubes seated in the base or back of the bill-file and extending through said base or back, near the upper portion of the latter, so that the hook-shaped cutting- 15 arms, connected at their lower ends by an integral cross-rod, or cross-piece, may be operated within vertically-disposed side guides connected with a base-plate secured to the face of the file-back, board, or base, near the 20 upper end of the latter, and occupying the intermediate portion of the board, back, or base, from the upper end edge of said board, and extending downwardly therefrom to openings made through said board, which openings align with vertical bottomless tubes se- 25 cured in a face-plate which carries the cutting-hooks, which latter after engaging the paper, bill, or the like cut out small disk-shaped portions of the same and force them down into the 30 tubes, repetitions of the operation forcing other disks of paper down the tubes until the disks have sufficiently accumulated therein to force the lowermost disks out at the lower ends of said bottomless tubes. The operating-le- 35 ver is hinged at its forward edge to the base-plate in any suitable manner, as by staples or the like, and the operating-lever, connect- ed with the cross-rod of the curved cutters or 40 punches (not puncturers) by forwardly-pro- jecting curved arms, serve to throw or oper- ate the hooks in connection with the serrated vertical bottomless tubes, so that the paper cut out of the bills or letters will, while ac- cumulating in said tubes, be forced down and 45 out at the lower ends of said bottomless tubes by the impact of the paper disks upon the paper disks already within the tubes, so that by operating the lever upon the newly-placed bill or the like the cut-out portions will be 50 forced out at the lower ends of the cutting-

tubes. The vertical side guides prevent lateral play of the cutting-hooks, so that they invariably enter the mouths of the bottomless tubes and insure absolute cuts of the paper to be perforated or cut out. The hooks 55 permit the papers, letters, &c., to be turned up thereon for inspection at any time before removal therefrom. In this connection is provided a removal or take-off frame having 60 arms which may be inserted into the tubes, and consequently through the perforations made in the papers by the hooks, in conjunc- 65 tion with said tubes. This take-off frame has a base-rod and integral vertically-extended hook-rods which are engaged by a looped 70 spring provided with end hooks for engaging the loops or eyes at the upper ends of the vertically-extended rods, so that by inserting the vertical rods into said vertical tubes while 75 the bills or letters yet remain upon the bill- 75 file the looped spring may be engaged with the hooks or loops at the upper ends of the vertically-extended rods and the papers may be removed and filed away for future use or reference.

In the accompanying drawings, forming part of this specification, Figure 1 is a view in perspective of a bill-file embody improvements of my invention. Fig. 2 is a view in perspective of the take-off frame and the 80 looped spring connected therewith through its hook-arms. Fig. 3 is a longitudinal sec- 85 tional view showing the tubes and hook-arms in full lines, the operating-lever in section, both the operating-lever and hooks being shown also in dotted lines in initial and sec- 90 ondary positions. Fig. 4 is a transverse ver- 95 tical sectional view taken on line 4-4 in Fig. 3 looking from the direction the arrows point in Fig. 3, showing the letters, bills, &c., in 90 position on the bill-file. Fig. 5 is a detail view showing the hooks and their integral connection detached from the bill-file. Fig. 6 is a detached plan view of the operating- 95 lever. Fig. 7 is a detail view in perspective of one of the vertically-disposed side guides within which the connected hooks ride verti- 100 cally as well as partially rotary when the controlling-lever is operated.

Referring by numeral to the accompanying

drawings, 1 is the base, back, or body of the bill-file, which serves to support the operative mechanism secured thereon, and this base, as shown in Fig. 4, is provided with 5 vertically-disposed circular openings 2, extending entirely therethrough. The face-plate 3 is secured by screws, rivets, or the like to the face of the file-back near the upper end of the face-plate, the upper end edge 10 of said face-plate occupying substantially the middle two-thirds portion laterally near the upper portion of said file-back. The operating-lever 4 is substantially spade shape in outline, the handle 5 being formed integral 15 therewith and provided near its upper end with an opening 5', which permits the entire device when put together properly to be suspended from a hook or nail when necessary and not in use in filing or inspecting bills and 20 letters. The side guides 6 and 7 oppose each other and have vertical half-tubes 8 and 9 provided with integral vertical flanges 10, extending in the direction of the length of the file-back, the upper portions of said half- 25 tubes and their integral flanges 6 being cut away or made shorter than the lower or inner portions of the same in order to permit the vertically-movable rock-shaft 13 to be turned back and the hooks 30 31, extended 30 above the upper end edge of the file-back, to permit of the inspection or removal of papers from the bill-file. The lower portions of said side guides 6 and 7 are provided with integral outwardly-projecting lugs 14 15, which 35 are provided with holes to receive screws or rivets 16, by which the said side guides are secured to the face-plate 3. Vertically-disposed bottomless tubes 17 and 18 are secured to the face-plate 3 near the two corners of 40 said plate at its lower longitudinal line and communicate with circular openings 2, extending entirely through the file-back to permit said bottomless tubes 17 and 18 to be emptied of the paper disks accumulating 45 therein. The upper ends of said bottomless tubes 17 and 18 are serrated or provided with teeth 21, which encircle the mouth of said tubes and project in alinement with the circumference of said tubes and permit the cutting 50 ends of said hooks 30 31 to enter vertically the serrated upper ends of said tubes 17 and 18 for a short distance and not only assist in cutting out disks from the paper, but also in forcing the disks thus cut down into 55 the tubes, and when said disks have accumulated sufficiently in said tubes to force the lowermost disks out at the open lower ends of said tubes in order to make room for the paper disks that are to follow. 60 The papers accumulating on the bottomless tubes may at any time be moved upwardly along said tubes, and while the hooks 30 31 are in engagement with the upper ends of said bottomless tubes the paper, letters, or 65 the like may be moved from said tubes up

and upon the said hooks one at a time for inspection or all at one time when necessary to remove them. The take-off wire 32 is angularly bent and has parallel depending arms 33 34, provided with loops 35 at their ends, 70 which loops are designed to and do engage with the inwardly-projecting fingers 36 of a centrally-looped wire 37. The depending arms 33 34, while the papers are resting on the file-back and the bottomless tubes are projecting upwardly through them, are inserted into the tubes, and the papers are lifted or moved up onto said depending arms, after which the arms of the take-off wire are engaged by the fingers 36 of the take-off wire, 80 and the papers, &c., may be then lifted from the file-back and suspended from a hook or nail to relieve the bill-file from the accumulation of papers and may be inspected afterward and later filed away for future reference, if desirable. The take-off frame or wire 85 virtually forms a temporary binder after it has been used to remove or lift the bills, &c., from the file-back and may be kept at hand for temporary use before being filed away. 90 The vertical cuts made by the hook-arms in connection with the serrated bottomless vertical tubes are assisted by the grooved and flanged vertical shouldered side guides for the reason that the upward and downward 95 movements of the operating-lever permit or cause both a vertical and rocking motion of the integral connecting-rod, from which the hooks project upwardly, and throw said hooks vertically and rearwardly when said operating-lever is raised and moves them forwardly over the bottomless tubes and, further, throws their cutting ends vertically downwardly into the serrated mouths of the bottomless tubes when said lever is operated to move downwardly or has been depressed, thereby not only causing the disks to be cut from the papers, but also forces the accumulating disks out at the open lower ends of said tubes, so 100 that papers can be cut out as rapidly as filed 105 without danger of choking said bottomless tubes. 110

The short hook-arms 50, formed integral with and projecting below and forwardly upon the lower face and at the edges of the operating-lever, engage the face-plate connecting the cutting-hooks and cause it to both lower and raise or lift said cutting-hooks and insure their proper action in connection with the serrated bottomless tubes when said lever is 115 operated upon the bills resting upon the upper ends of the serrated bottomless tubes before referred to. 120

While I have shown as one form of the structure an operating-lever 4, I desire to 125 state in this connection that this lever is only one form for the manipulation of the device and that I do employ a form of structure in which the lever is omitted and the hands of the operator are used to force the hooks 30 31 130

down through the paper or papers into the serrated tubes 21, dispensing entirely with said lever, if desirable, while I may and do in many instances retain the lever as a component part of this structure.

It should be noticed that the lower edge of the operating-lever 4 is connected with the face-plate 3 by staples 60, seated in the face-plate 3 and passed through openings near the lower edge of the operating-lever 4 and practically serving as hinges for said operating-lever.

Having thus fully described my invention, what I claim, and desire to secure by Letters Patent, is—

1. In a bill-file, of the class described, the combination of the file-back; the face-plate secured thereon near the upper end edge of the file-back; the flanged and shouldered side guides connected to said face-plate; the bottomless tubes serrated at their upper ends and secured in said face-plate in alinement with openings in said file-back; cutting-hooks formed integral with a cross-rod; a shovel-shaped operating-lever hinged at its lower edge to said face-plate, and provided with hook-arms made integral therewith, projecting from its lower face, at the edges of the latter, and engaging the cross-rod connecting said cutting-hooks for imparting both vertical and rock motion to said cutting-hooks, and

guiding the cutting ends of said cutting-hooks vertically down into the serrated mouths of said bottomless tubes, to cut disks from a paper and force said disks down into the bottomless tubes, and, as accumulated, out at the alined openings in said file-back; substantially as specified.

2. In a bill-file, of the class described, the combination of the file-back; the flanged and shouldered side guides connected to said face-plate; the bottomless tubes serrated at their upper ends and secured in said face-plate in alinement with openings in said file-back; cutting-hooks formed integral with a cross-rod; 45 said cutting-hooks having both a vertical and a rocking motion when operated by hand-pressure and having cutting ends that enter the serrated mouths of said bottomless tubes, to cut disks from a paper and force said disks 50 down into the bottomless tubes, and as accumulated therein to force said disks out at the bottomless tubes, and through openings in said file-back, which openings are in alinement with said bottomless tubes; substantially 55 as specified.

In testimony whereof I affix my signature in presence of two subscribing witnesses.

GEORGE H. MAURER.
